INVENTOR.
J. R. Fricke,

UNITED STATES PATENT OFFICE.

JOSEPH R. FRICKE, OF PITTSBURG, PENNSYLVANIA.

LIGHTNING-CONDUCTOR.

SPECIFICATION forming part of Letters Patent No. 311,115, dated January 20, 1885.

Application filed February 21, 1884. (No model.)

To all whom it may concern:

Be it known that I, JOSEPH R. FRICKE, a citizen of the United States, living in the city of Pittsburg, county of Allegheny, and State 5 of Pennsylvania, have invented a new and useful Improvement in Lightning-Conductors; and I do declare the following to be a full, clear, and exact description of the same, such as will enable any person skilled in the art or 10 science to which it appertains most nearly to make, construct, and use the same.

My invention relates to an improvement in lightning-conductors; and it consists in a solid rod the point of which is attached to its upper 15 end, a connecting-tube, and cable or conductor which is connected to the solid rod by the tube, as will be more fully described herein-after.

The object of my invention is to provide a 20 stiff support for the point of a flexible wire-cable lightning-conductor, so that the upper end of the conductor can be carried any desired distance above the top of the house.

Figure 1 is a side elevation, partly in section, 25 of a conductor embodying my invention. Fig. 2 is a side elevation of the rod alone. Fig. 3 is a vertical section of the connecting-tube alone. Fig. 4 is a detached view of the cable. Fig. 5 is a perspective of the point and its at- 30 tachments.

G represents a cable conductor, which is preferably formed of copper wires, and which is flexible. Passed down over the top of this

cable is the connecting-tube B, also preferably made of copper, and which will be of a length 35 proportioned to the distance the point is to be raised above the top of the house.

In the top of the tube B is placed the solid copper rod A, which has its upper end, E, made screw-threaded, so as to receive the tip 40 D. This rod A serves to brace the pipe or tube B, to make connection with the cable, and to support the tip. The screw-threaded end of the rod A projects just far enough above the pipe or tube to allow the base of the tip to 45 rest on the top of the tube, and thus form a neat finish and a continuous conducting surface. The cable being flexible, it becomes necessary to attach to it a rigid support for the tip, so as to keep the tip in a vertical position. 50

Having thus described my invention, I claim—

1. A flexible lightning conductor, G, in combination with the tube B, applied to its upper end, the tip D, applied at the upper end 55 of the tube, and the rod A, supporting said tip, substantially as shown.

2. The combination of the cable conductor, a tube applied to its upper end, the rigid rod, which is placed in the tube, and the tip, sub- 60 stantially as set forth.

JOSEPH R. FRICKE.
